UNITED STATES PATENT OFFICE.

BENJAMIN BURGESS, OF DANVILLE, ILLINOIS.

RAIL-ANCHOR.

SPECIFICATION forming part of Letters Patent No. 717,808, dated January 6, 1903.

Application filed August 18, 1902. Serial No. 120,074. (No model.)

To all whom it may concern:

Be it known that I, BENJAMIN BURGESS, a citizen of the United States, and a resident of Danville, in the county of Vermilion and State of Illinois, have invented a new and Improved Rail-Anchor, of which the following is a full, clear, and exact description.

This invention relates to a means for gripping or clamping a railway-rail so as to form an anchor for wrecking purposes. It may be used in a great number of ways, as will be apparent, notably as a means for anchoring a tackle by which cars may be drawn back on the track.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is a plan view with a part of the rail broken away. Fig. 2 is a side view; and Fig. 3 is a perspective view of the device, showing it detached from the rail.

The anchor comprises two arms *a*, which have each at one end an upwardly and inwardly projected extension *a'*. These extensions *a'* are pivotally connected together by a pin *b* or the equivalent thereof, and said extensions form a bridge which connects the arms *a* and rises over the ball of the rail. Each arm *a* is formed on its inner side with a shoulder *c*, and these shoulders are adapted to engage the ends of the fish-plates, as shown in Fig. 1, said shoulders bearing against the web of the rail and under the ball thereof. The free ends of the arms *a* have chains *d* engaged therewith, and the said chains are adapted in turn to be connected with the railway-car or other apparatus in connection with which the anchor is used.

In using the anchor the arms *a* are laid, respectively, on the sides of the rail, and the bridge formed by the extensions *a'* is caused to pass over the ball of the rail, thus placing the shoulders *c* alongside of the web of the rail under the ball and bearing with their square sides against the end edges of the fish-plates at the rail-joint. Strain is applied to the anchor through the medium of the chains *d*, and it will be observed that stress on these

chains will cause the arms *a* to move inward toward each other, thus insuring a proper engagement with the fish-plates. 55

It will be observed that in this device no cross-strain is involved and that its operation does not depend on any pinching action. The gibs or shoulders *c* abut against the fish-plates and are held engaged therewith by the 60 pull of the chains *d*.

The manner of using the invention will be apparent to all persons skilled in the art, and this need not be explained here. The device may be used in many ways and branches of 65 the railway wrecking and constructing art.

Various changes in the form and details of my invention may be resorted to without departing from the spirit of my invention. Hence I consider myself entitled to all forms 70 of the invention as may lie within the intent of my claims.

Having thus described my invention, I claim as new and desire to secure by Letters Patent— 75

1. A rail-anchor, comprising two arms connected to each other at one end to swing toward and from each other, each arm having at a point intermediate its ends an inwardly-extended shoulder projecting under the ball 80 of the rail to engage the fish-plates of the rail-joint.

2. A rail-anchor, comprising two arms, and means extending transversely of the rail and connecting said arms to each other at one end to swing toward and from each other, each arm having at a point intermediate its ends a shoulder, and said shoulders being extended inward under the ball of the rail to engage the ends of opposite fish-plates of a joint-rail. 90

3. A rail-anchor, comprising two arms having upwardly and inwardly bent extensions pivotally connected together and forming a bridge adapted to extend over the ball of the rail to hold the arms against opposite sides 95 of the web below the ball, and said arms having shoulders thereon arranged to engage the fish-plate of a joint in the rail.

4. A rail-anchor, comprising two arms having upward and inwardly bent extensions 100 pivotally connected together to form a bridge, said bridge being adapted to extend over the ball of the rail to hold the arms at opposite sides of the web under the ball, and means

in connection with the free ends of the arms for drawing on the anchor.

5. A rail-anchor, comprising two arms connected to each other at one end to swing toward and from each other, each arm having thereon at a point intermediate its length an inwardly-extended shoulder projecting under the ball of the rail into engagement with the web thereof, and a means in connection with

the free ends of the arms for connecting them to with a car or the like.

In testimony whereof I have signed my name to this specification in the presence of two subscribing witnesses.

BENJAMIN BURGESS.
